UNITED STATES PATENT OFFICE.

JAMES L. GARNETT, OF ST. LOUIS, MISSOURI, ASSIGNOR TO EMIL A. PETERSON, OF APPLETON, WISCONSIN.

HYDRAULIC LATCH.

1,077,062.

Specification of Letters Patent.

Patented Oct. 28, 1913.

Application filed December 5, 1912. Serial No. 735,005.

To all whom it may concern:

Be it known that I, JAMES L. GARNETT, a citizen of the United States, residing at St. Louis, State of Missouri, have invented 5 new and useful Improvements in Hydraulic Latches, of which the following is a specification.

My invention relates to improvements in hydraulic latches, designed more particularly for securing the doors of baling 10 presses, etc., but also adapted for use in any relation where a latch of great holding power is desired.

The objects of my invention are to provide 15 a form of latch which can be easily manipulated to holding position, but which will be unyielding in such position. Also to provide a form of latch which will yield without release, preparatory to its movement into releasing position, and thus not only permit a free releasing movement, but also avoid destructive reactions where the latch is subjected to a heavy pressure of 20 material, capable of a degree of resilient expansion.

In the drawings my invention is illustrated as embodied in a baling press, to secure the doors at the compression end of the box or casing.

30 Figure 1 is a front elevation of such a press. Fig. 2 is a side elevation of the same. Fig. 3 is a plan view with the cap removed, and the latches in holding position. Fig. 4 is a detail view of one of the 35 latches showing a fragment of the door to which it is applied and showing the door supporting beams in cross section. Fig. 5 is a detail sectional view, drawn on line $x-x$ of Fig. 4.

40 Like parts are identified by the same reference characters throughout the several views.

The baling press shown in the drawings may be of any ordinary form of construction, except as to the means for securing the 45 bale releasing doors A, B, C and D. The press illustrated has front and rear walls E and side walls F of which the doors are a continuation. The walls are reinforced by 50 angle iron or I-beams G, and the doors are similarly reinforced by beams H and J, which are provided with hinge knuckles embracing the posts K. M are cap members, N a movable platen and O is a piston or 55 piston rod extending through the bottom

wall of the press. All of these parts in their specific features of construction being unrelated to my invention, it is not deemed necessary to describe them in further detail. It will be observed, however, that the beams H of the doors A and B extend beyond the doors as indicated at 2, and the inner faces of these extensions 2 are provided with cleats 4 against which the margins of the doors C and D respectively abut, at the ends 60 opposite those to which the hinges are connected. Stirrup shaped latches 6 are adapted to be adjusted over the projecting ends 2 of the beams H, the latches 6 being carried by the doors C and D and arranged to co- 65 operate with the cleats 4 to lock all the doors A, B, C and D together. Each latch 6 is hinged at 8 to a coupling member 10, which is pivotally connected with a pair of connecting rods or bars 12. The latch hinge 8 is adapted to permit the latch to swing over the beam end 2 after which a pull upon the bars 12 draws it inwardly and binds the beam (and the door to which it is secured), 70 firmly in position. 75

A cylinder 16 is mounted upon each of the doors C (or D), and a piston 18 therein is provided with a rod 20 projecting through the rear end of the cylinder and coupled at 22 to the bars 12, whereby movement of the piston backwardly or away from the position of the latch, draws the latch to locking position over the beam end 2, as above explained. Power may be applied to the piston by admitting liquid to the cylinder 85 through a pipe 24, past a valve 26, which may be a three way valve, adapted to permit the liquid to exhaust through an outlet duct or port 28. A liquid such as water, being admitted under pressure to the cylinder, the piston will move backwardly and the latch, if in position on the beam 2, will draw the beam and the door to a tightly closed position. If no resistance is applied to the door, a light pressure of the liquid upon the piston will be sufficient, and the pressure may be increased to any desired extent in case 90 the latch is employed to close doors against a resistance. When the door has been fully closed, the valve 26 may also be closed 95 whereupon the liquid in the cylinder will prevent any retractive movement of the piston regardless of the pressure upon the door. But to then release the latch and permit the door to open, the valve 26 may be opened 100 105 110

for the escape of the liquid, whereupon the piston moves freely inwardly and allows the latch to swing free from the beam end 2. Where the pressure applied to the door is 5 resilient as is the case with most baled materials, the valve 26 may be opened gradually to permit a slow expansion of such material and prevent destructive reactions such as might break the door from its hinges. 10 When the resilient pressure of the bale has been thus relieved, the latch may be removed from the beam end as above explained. Where great strains are encountered, the bars 12 are preferably supported in channels 30 in the cylinder wall. The piston rod 15 is also preferably passed through the rear wall of the cylinder, serving as a pressure rod instead of a tension rod, and it may be short and heavy thus securing a compact 20 structure of great strength, in which packing is unnecessary except for the piston, the liquid receiving end of the cylinder being wholly closed, except at the inlet and outlet ports. The cylinder is preferably secured to 25 the door by means of an angle iron chain 34. The cleats 4 in the beam ends 2 are provided in order that one latch may lock two doors, *i. e.* a door which carries a cylinder and latch and a door which carries a beam J. 30 Where only one door is to be locked by a latch supported from a fixed wall, the notch may be omitted. The specific structure of the latch and the part which it engages (the beam having a projecting end 2), are also 35 to be understood as illustrated and described merely as preferred forms, where my invention is applied to a baling press and subjected to heavy strains. Any suitable style 40 of latch and catch may be used in substitution, as desired.

I claim—

1. The combination with a door, a support, a latch connected with the support and adapted to engage the door, and hydraulic 45 means for permitting a partial movement of the latch and door preparatory to the release of the latch from the door.

2. The combination with a baling press door of a support, a member mounted to 50 slide upon said support, a door engaging latch pivoted to said member, a cylinder mounted upon said door, a piston therein connected with said member, whereby fluid 55 may be admitted to the piston to hold said member with the latch in door locking position.

3. The combination with a baling press door, of a support, a member mounted to 60 slide upon said support, a latch pivoted to said member and adapted to engage the door, and hydraulic means for actuating said member to lock the latch in door engaging 65 position.

4. The combination with a latch, of a device 70 for receiving a body of liquid in posi-

tion to prevent latch release from locking position, a latch actuating member adapted to be controlled by such body of liquid, means for delivering liquid to said device, and means for permitting its gradual discharge therefrom; said latch actuating member being adapted by its movement to permit a partial opening movement of the door preparatory to the latch releasing movement. 75

5. The combination with a latch, of a device for receiving a body of liquid in position to prevent latch release from locking position, a latch actuating member adapted to be controlled by such body of liquid, 80 means for delivering liquid to said device, and means for permitting its gradual discharge therefrom, said latch being movable in line with its holding pressure, and also adapted for independent movement at an 85 angle thereto.

6. The combination with a latch, of a liquid container, a movable member therein adapted to be actuated by liquid pressure, connections between the latch and said movable member, said latch being also adapted to swing upon said connections into and out of locking position; and means for closing said container with a body of liquid 90 therein. 95

7. The combination with a compartment provided with a door, a latch adapted to lock said door in closed position, a latch holding member to which the latch is pivoted for swinging movement into and out of locking position, means for moving the latch holding member to cause the latch to bind in locking position, and a liquid stop adapted to prevent a releasing movement 100 of the holding member. 105

8. The combination with a compartment provided with a door, a compartment wall provided with a cylinder secured thereto, a piston in the cylinder, a door holding latch pivotally connected to swing into and out of holding position with reference to said door, connections between the latch and piston adapted to utilize movements of the latter to bind and release the latch when in holding position, and valve mechanism controlling the delivery and discharge of liquid to and from the cylinder respectively. 110

9. The combination with a pair of baling press doors, located in intersecting planes, 115 of a member mounted to slide upon one of said doors, a latch connected with said member and adapted to engage the other door and hydraulic means for actuating said member to hold the latch in door engaging 120 position; said hydraulic latch holding means being adapted to permit a gradual movement of said member and latch sufficient to allow the door to partially open preparatory to a disengagement of the latch. 125 130

10. The combination with a compartment such as the casing of a baling press, of a set of hinged doors forming the walls thereof and arranged in pairs with the swinging 5 margins of the doors of each pair in proximity when the doors are closed, a swinging latch carried by one of the doors, a projection carried by the other door in position to be engaged by the latch, a cylinder on the 10 latch supporting door, a piston therein, connections between the piston and latch,

and means for admitting liquid to and discharging it from, the cylinder, said piston being adapted to move the latch in a direction at right angles to latch releasing move- 15 ment.

In testimony whereof I affix my signature in the presence of two witnesses.
